CLAIM

The ornamental design for a computerized in-vitro diagnosis machine, as shown and described.

DESCRIPTION

FIG. 1 is a front view showing our design for a computerized in-vitro diagnosis machine;

FIG. 2 is a right side view thereof;

FIG. 3 is a left side view thereof;

FIG. 4 is a back view thereof;

FIG. 5 is a top view thereof;

FIG. 6 is a bottom view thereof; and,

FIG. 7 is a front perspective view thereof.

1 Claim, 7 Drawing Sheets
